UNITED STATES PATENT OFFICE.

MARSHALL E. GRAVES, OF LOWELL, MASS., ASSIGNOR TO THE SHOREY SPRING BED AND SHADE ROLLER COMPANY, OF SAME PLACE.

BED-BOTTOM.

SPECIFICATION forming part of Letters Patent No. 278,330, dated May 29, 1883.

Application filed February 3, 1883. (No model.)

To all whom it may concern:

Be it known that I, MARSHALL E. GRAVES, a citizen of the United States, residing at Lowell, in the county of Middlesex and Commonwealth of Massachusetts, have invented certain new and useful Improvements in Bed-Bottoms, of which the following is a specification.

My invention relates to a bed-bottom having slats and longitudinal coiled springs attached to the ends of said slats and to the frame of the bed-bottom, and to means of flexibly connecting the slats to each other.

In the accompanying drawings, Figure 1 is a plan of the bed-bottom; Fig. 2, a side elevation of the same standing on end; Fig. 3, an end elevation of said bed-bottom; Fig. 4, a plan of the end of a slat provided with an end plate, and the ends of two springs attached to said plate; Fig. 5, a vertical cross-section of two slats connected by hooked wires and staples or eyes; Fig. 6, an edge or side elevation of a part of a slat, the end being broken away to show the slot and pin; Fig. 7, a plan of a part of a slat provided with slots, into which the ends of the springs are inserted.

A is a rectangular frame of any suitable construction, having preferably end bars, B B, provided with inwardly-inclined upper surfaces, as shown in Fig. 2, and having also metallic attaching-plates C C secured to the outer sides of said end bars, and provided with holes C' near the upper edges of said plates C C, into which holes the hooked outer ends, E', of the longitudinal coiled springs E are hooked in the usual manner; but the outer ends of the springs may be connected to the frame A in any well-known or convenient manner, such connection forming no part of the invention herein described. The longitudinal coiled springs E do not (as is usually the case with such springs) extend from end to end of the bed-bottom, the principal part of the said bed-bottom consisting of elastic wooden slats F, placed longitudinally. To each end of each slat is attached one or more of the springs E by the inner ends of said springs. The ends of the slats are preferably fastened to the springs by forming hooks or eyes E² in the inner ends of the springs, inserting these hooks or eyes E² in the slots F', cut in the ends of the slats, and then inserting pins F² in the slats

from edge to edge of the same, at right angles to and crossing said slots F', and passing through the hooks or eyes E², as shown in Figs. 6 and 7. Another method of attaching the springs to the slats is shown in Figs. 1, 2, and 4, where the ends of the slats are slotted transversely, and in the slots thus formed are inserted metallic plates F³, secured in place by rivets F⁴, passing down through the slats and plates F³, these plates being provided with holes F⁵, into which are hooked the hooks or eyes E², formed on the inner ends of the springs E. In either case the springs and slats are jointed or flexibly connected together, so that each spring and each slat may take the curvature due to its own elasticity to avoid giving a permanent bend or set to the wire near the end of the spring, (when the greater part of the weight is applied at or near the end of the slat,) as would happen if the ends of the springs were rigidly attached to the slats. The slats, while intended to be sufficiently elastic, will not bend in so sharp a curve as springs, and cannot of course be stretched, and are therefore not so liable to sag in the middle as springs running the whole length of the bed-bottom. The slats and springs combined as above described are cheaper than springs reaching from end to end of the bed-bottom, because the slats are cheaper than springs of the same length when stretched, and also because there is less waste of the wire used to make the springs, inasmuch as a piece of wire (at the end of the coil from which the wire is taken) too short to make one such long spring may yet be long enough to make one, two, or more of the springs required for a bed-bottom of the construction herein described. Partly to prevent the slats from turning on edge when only a single spring is used at each end of a slat, and partly to prevent lateral displacement or spreading apart of the slats, I connect the slats to each other laterally by wires G, provided at each end with hooks G', which engage with eyes H or staples inserted in the edges of the slats, the hooked wires being long enough to allow any slat, when pressed upon, to move downward very slightly before drawing down the adjacent slats.

I claim as my invention—

1. The combination, in a bed-bottom, of a

series of slats flexibly connected together, and two series of parallel coiled springs connecting the ends of said slats to the frame of said bed-bottom, as and for the purpose specified.

5 2. In a bed-bottom, the combination of a series of parallel slats flexibly connected together, and two series of parallel coiled springs lying in the same direction with said slats, and connecting the ends of said slats to said frame 10 of said bed-bottom, as and for the purpose specified.

3. The combination of a series of parallel slats and wires provided with hooks, and means

of connecting said hooks to the edges of said slats, as and for the purpose specified. 15

4. The combination of a series of slats provided with eyes at the edges of said slats, and the wires provided with hooks, as and for the purpose specified.

In testimony whereof I have hereunto signed my name this 25th day of January, A. D. 1883.

MARSHALL E. GRAVES.
